Primary Examiner—Ian Simmons(74) *Attorney, Agent, or Firm*—Fattibene & Fattibene; Paul A. Fattibene; Arthur T. Fattibene(57) **CLAIM**

The ornamental design for a dental material placement and applicator device, as shown and described.

DESCRIPTION

FIG. 1 is a perspective view of a dental material placement and applicator device showing our new design; FIG. 2 is a side elevation view thereof, the other side being the same;

FIG. 3 is a top view thereof;

FIG. 4 is a bottom view thereof;

FIG. 5 is a rear end view thereof; and,

FIG. 6 is a front end view thereof.
